UNITED STATES PATENT OFFICE.

LAURA S. MYERS, OF PEN MAR, PENNSYLVANIA.

CURTAIN-POLE LIFTER.

1,120,962.

Specification of Letters Patent. Patented Dec. 15, 1914.

Application filed July 17, 1912, Serial No. 710,089. Renewed October 29, 1914. Serial No. 869,351.

To all whom it may concern:

Be it known that I, LAURA S. MYERS, a citizen of the United States, residing at Pen Mar, in the county of Franklin, State of Pennsylvania, have invented certain new and useful Improvements in Curtain-Pole Lifters; and I do hereby declare the following to be a full, clear, and exact description of the invention, such as will enable others skilled in the art to which it appertains to make and use the same.

This invention relates to curtain pole lifters and has for an object to provide an extremely simple device by which curtain poles may be seized and removed from their supporting brackets without the necessity of resorting to step ladders and climbing upon the latter to gain access to the pole.

A further object of the invention is to provide a curtain pole lifter having divergent hooks adapted to bear against one side of the pole, and an intermediate hook adapted to bear against the opposite side of the pole, whereby the pole will be securely gripped and held against accidental release.

With the above objects in view the invention consists of certain novel details of construction and combination of parts herein-after fully described and claimed, it being understood that various modifications may be made in the minor details of construction within the scope of the appended claim.

In the accompanying drawing forming part of this specification:—Figure 1 is a front elevation of the invention in operative position upon a curtain pole. Fig. 2 is a plan view of the device. Fig. 3 is an end elevation of the device showing the grab hook prior to movement to operative position. Fig. 4 is a detail perspective view of the device.

Referring now to the drawing in which like characters of reference designate similar parts, 10 designates a long rod which 45 constitutes the handle of the device, the rod

being equipped at one end with a fork 11 the arms 12 of which diverge from the rod and terminate in hooks 13 which are adapted to bear against the same side of the curtain pole 13. A rod 14 is slidably fitted upon the handle by means of strap brackets 15, this rod projecting forwardly between the arms 12 of the work and terminating in a grab hook 16 adapted to engage the opposite side of the curtain pole from the hooks 13 of the arms, substantially midway between the said hooks 13.

In applying the device to a curtain pole, the slide rod 14 is slid downwardly along the handle, and the handle then is manipulated to position the hooks 13 upon the curtain pole. The rod 14 is now slid upwardly, the hook 16 meanwhile impinging against the pole and being deflected outwardly thereby, the rod yielding during such deflection, and returning to normal position upon the rod being slid upwardly sufficiently to position the grab hook in registration with the pole whereby the grab hook engages snugly with the pole and on the opposite side from the hooks 13.

What is claimed, is:—

A curtain pole lifter including a handle, a fork carried at the tip of said handle having divergent arms terminating in half round hooks adapted to engage one side of a curtain pole, and a resilient slide rod carried on said handle and projecting into the space between said arms, said rod terminating in a half round hook adapted to align with the first named hook and to engage the opposite side of the curtain pole from the first named hooks.

In testimony whereof, I affix my signature, in presence of two witnesses.

LAURA S. MYERS.
